UNITED STATES PATENT OFFICE.

HERBERT G. MEARS, OF NEW YORK, AND HENRY W. AYLWARD, OF BROOKLYN, NEW YORK, ASSIGNEES, BY MESNE ASSIGNMENTS, TO THE AUTO-IGNITER COMPANY, OF NEW YORK, N. Y., A CORPORATION OF NEW JERSEY.

IGNITER FOR INTERNAL-COMBUSTION ENGINES.

SPECIFICATION forming part of Letters Patent No. 732,365, dated June 30, 1903.

Application filed November 19, 1902. Serial No. 131,972. (No model.)

To all whom it may concern:

Be it known that we, HERBERT G. MEARS, residing in the borough of Manhattan, and HENRY W. AYLWARD, residing in the borough of Brooklyn, city of New York, State of New York, both citizens of the United States, have invented a certain new and useful Improvement in Igniters for Internal-Combustion Engines, of which the following is a description.

10 Our invention relates to various new and useful improvements in igniters for internal-combustion engines; and the improvements have been designed particularly for use with high-speed gas and gasoline engines employing electric ignition. As is well known, it is possible to effectively regulate the speed of engines of this type within relatively wide limits merely by "timing" the ignition, where-by the explosion will take place at any part 15 of the movement of the piston on the explosion-stroke or while the piston is actually nearing the end of the compression-stroke. Our invention is particularly designed for use with internal-combustion engines of this 20 type, for the reason that we are enabled by very simple mechanism to regulate the timing of the spark. In its preferred form the invention also possesses the advantage over devices for the purpose heretofore used of 25 being entirely concealed by the fly-wheel, so as to be protected from injury, while at the same time the general compactness of the device will be increased.

Our improved igniter is of the type invented by Le Pontois, employing a magnet with a coil surrounding one of its poles and with an inductor movable with respect to said coil. As suggested by Le Pontois, this inductor may be formed of the engine fly-wheel itself, 40 and the relative movement between the inductor and pole may be effected by merely cutting a gap in the fly-wheel, which gap may be left as an air-space or be filled with some non-magnetic material, like bronze.

45 The objects of our present invention are, first, to provide improvements in igniting apparatus of the Le Pontois type by means of which the timing of the ignition can be accurately and readily effected, and, second,

to provide improvements in such apparatus 50 by means of which the component parts thereof are inclosed by the fly-wheel, so as to be thereby completely protected. Preferably these objects are accomplished in one and the same apparatus.

55 In order that the invention may be better understood, attention is directed to the accompanying drawings, forming part of this specification, and in which—

Figure 1 is a side view of the fly-wheel of 60 an internal-combustion engine, showing the improved igniting apparatus in its preferred form; and Fig. 2, a section on the line 2 2 of Fig. 1.

65 In both of the views corresponding parts are represented by the same reference-numbers.

The engine fly-wheel 1 is mounted on a shaft 2 and is provided with an overhanging rim 3 and a hub 4. Loosely mounted on the hub 70 4, so that the hub will be capable of independent rotation with respect to the same, are two bearing-rings 5 5, formed with cast lugs or ears 6. These lugs or ears are screwed or bolted to soft-iron pole-pieces 7 8, which are 75 of any suitable form and construction. Connecting the pole-pieces 7 8 are separate permanently-magnetized bars 9 9, held in position by clamping-plates 10, screwed to the pole-pieces. Like poles of all the magnets 80 co-operate with one of the pole-pieces and the other poles of the magnets with the other pole-piece, so that the pole-pieces 7 and 8 practically constitute the two poles of a powerful magnet, whose inductor is the overhanging rim 3 of the fly-wheel. These pole-pieces co-operate as closely as possible with the fly-wheel, so as to secure the maximum inductive effect in operation. The pole-piece 7 is reduced at its outer extremity to form 90 a core 11, or instead a separate soft-iron core, laminated or not, may be employed. This core is surrounded by a coil 12, whose terminals lead to binding-screws 13, with which connection is made to the exterior circuit. On the under face of the rim 3 is cut a gap 14 of the desired length and which may be left open to form an air-gap or be closed 95

by a non-magnetic material, like bronze. It will be evident that if the fly-wheel were not provided with such a cut-away portion its rotation with respect to the core 11 would produce no effect in the coil; but by employing such a cut-away portion the rotation of the fly-wheel results in the generation of a current in the coil, the effect being the same as if the inductor were moved bodily toward and away from the coil.

We make use of a polar extension 15 of any desired size and shape, carried by the pole-piece 7, as shown, in order that the magnetic circuit may not be broken at any time to thereby permit the magnets to become weakened, as would otherwise be the case. This polar extension is so located with respect to the pole-piece 7 and the gap 14 is so proportioned in length that the front of the gap does not reach the polar extension 15 until the rear end of the gap has traversed a part of its distance over the pole-piece. Thus, having reference to the parts as shown in Fig. 1, it will be seen that although the magnetic circuit is broken at the core 11 by the gap covering the same (the effect being the same as if the inductor were moved bodily from the core) the magnetic circuit is still closed at this pole through the polar extension 15. On the other hand, when the magnetic circuit tends to become opened by the gap passing over the extension 15 the magnetic circuit will be kept closed between the core 11 and the inductor.

In order to properly time the spark, it is obvious that it is only necessary to provide a mechanism for quickly and conveniently adjusting the coil 12 circumferentially with respect to the fly-wheel, so that the gap or cut-away portion 14 will coöperate with the coil at any desired time in its rotation. For this purpose we illustrate a pair of links 16, pivoted to the pole-pieces 7 and 8 and connected at their ends on opposite sides of the pivot of a hand-operated lever 17 within convenient reach of the operator. Any convenient means may be employed for retaining the lever 17 in any position of its adjustment—as, for example, by imposing some sort of frictional resistance in its pivot.

It will be understood that if the present improvements are to be used in connection with an internal-combustion engine in which timing of the spark is not desired the bearing-rings 5 may be arranged so as to be incapable of independent circumferential adjustment with respect to the fly-wheel—as, for example, by utilizing one or both of the links 16 and by connecting the same at their free ends to an immovable abutment. Such an arrangement will possess the important advantage over existing constructions of concealing the igniting mechanism entirely by the fly-wheel, so as to protect it from injury, and of effecting a material saving in space, which is of high importance in some arts—as, for example, when the engine is employed

on an automobile. It will also be understood that while it is desirable that the igniting mechanism should be entirely concealed within the fly-wheel that part of our invention which provides for a convenient and effective circumferential adjustment of the igniter with respect to the fly-wheel can be utilized in other constructions, including those in which the igniting device is arranged exteriorly of the fly-wheel.

Having now described our invention, what we claim as new therein, and desire to secure by Letters Patent, is as follows:

1. The combination with a fly-wheel having a cut-away section, of a magnet with respect to whose pole the fly-wheel moves, a coil surrounding said pole, and means for directly adjusting the magnet circumferentially with respect to said fly-wheel, substantially as and for the purposes set forth. 85
2. The combination with a fly-wheel having a cut-away portion, of an induction-generator concentrically mounted with respect to said fly-wheel, and means for adjusting said generator concentrically, substantially as and for the purposes set forth. 90
3. The combination with a fly-wheel having a cut-away portion, of an induction-generator with respect to which the fly-wheel rotates, said generator being mounted within the inclosing ring of the fly-wheel so as to be protected thereby, substantially as and for the purposes set forth. 95
4. The combination with a fly-wheel having a cut-away portion, of an induction-generator mounted within the fly-wheel, and means for adjusting said generator concentrically to the fly-wheel, substantially as and for the purposes set forth. 105
5. The combination with a fly-wheel having a cut-away portion, of an induction-generator concentrically mounted with respect to said fly-wheel, and means for adjusting said generator circumferentially, substantially as and for the purposes set forth. 110
6. The combination with a fly-wheel having a cut-away portion, of a sleeve mounted on the hub of said fly-wheel and with respect to which the fly-wheel rotates, and an induction-generator carried by said sleeve, substantially as and for the purposes set forth. 115
7. The combination with a fly-wheel having a cut-away portion, of a sleeve mounted on the hub of said fly-wheel and with respect to which the fly-wheel rotates, and means for adjusting said generator circumferentially with respect to the fly-wheel, substantially as and for the purposes set forth. 120
8. The combination with a fly-wheel having a cut-away portion, of a sleeve mounted on the hub of the fly-wheel, a series of magnets carried by said sleeve, a pole-piece for said magnets having a core, and a coil surrounding said core, substantially as and for the purposes set forth. 125
9. The combination with a fly-wheel having a cut-away portion, of a sleeve mounted

on the hub of the fly-wheel, a series of magnets carried by said sleeve, a pole-piece for said magnets having a core, a coil surrounding said core, and means for adjusting said

5 sleeve independently of the fly-wheel to effect a circumferential adjustment of said coil, substantially as and for the purposes set forth.

10. The combination with a fly-wheel having a cut-away portion, of a magnet mounted concentrically to the fly-wheel, a pole-piece for said magnet coöperating with the rim of the fly-wheel, a coil on said pole-piece, and a polar extension for said pole-piece coöper-

ating with the fly-wheel rim, substantially as 15 and for the purposes set forth.

This specification signed and witnessed this 1st day of November, 1902.
